Specification for Design.

Patented Nov. 30, 1920.

Application filed May 6, 1920. Serial No. 379,419. Term of patent 14 years.

To all whom it may concern:

Be it known that I ARTHUR L. BREITENSTEIN, a citizen of the United States, resident of Akron, in the county of Summit and State of Ohio, have invented a new, original, and ornamental Design for Vehicle-Tires, of which the following is a specification, reference being had to the accompanying drawing, forming part thereof.

In the accompanying drawing:

Figure 1 represents an elevation of a sec-

tion of vehicle tire showing my improved design; Figs. 2 and 3 represent sections taken in the planes indicated by the lines II—II, III—III, respectively, Fig. 1.

I claim:

The ornamental design for a vehicle tire, substantially as shown.

Signed by me, this 21 day of April, 1920.

ARTHUR L. BREITENSTEIN.
